CENTER FILLER AND DRAFT GEAR STOP

Thomas A. Collison, Mount Vernon, Ill.

Application August 25, 1945, Serial No. 612,660

11 Claims. (Cl. 213—57)

1
My invention relates to center fillers for center sills of railway cars, and rear draft gear stops therefor.

In making center filler members which serve as bracing members for the center sill and usually incorporate the rear stops for the draft gear, it has been customary to provide castings for this purpose, which are riveted to the center sill. These castings are expensive to make and are very heavy. Some attempt at building up a center sill filler member and brace and rear draft gear stop of numerous pieces that are welded together has been made. However, the attempts to produce such welded structure have required the use of many small parts and specially shaped pieces, which had to be either forged or otherwise formed in a relatively expensive manner, and a rather complicated structure, with not as great saving in cost and weight as is desirable, resulted.

It is a purpose of my invention to provide a center sill filler and brace, which also serves the usual purpose of providing a king pin bearing at the point where the bolster intersects the center sill and having rear stop means for the draft gear, which is made of a small number of easily formed parts, which can be readily welded to each other to form the complete unit, and in which excessive weight has been eliminated without sacrificing strength where it is needed.

My invention more particularly comprises a pair of flanged side plate members that are adapted to be secured to the center sill members and which are provided with rear draft gear stops at one end thereof, which are suitably reinforced to withstand the blows to which said stop members are subjected, which side plate members are connected by means of a transverse bracing member including a plate-like member having a bracing member welded thereto, which bracing member is generally H-shaped in vertical and horizontal section, but which is provided with socket forming portions in its connecting web portion that provide the socket for the king pin.

One of the great advantages of using plates and other rolled shapes to build up the center sill filler member and brace is that variation in thickness of the parts can be held to a minimum, which is not possible with castings, these varying considerably over and under the proportions of the parts desired in the different castings, resulting in considerable loss of castings or undesirable increase in weight. Jigs can be provided for holding the various elements of my welded construction in place while the center sill filler member and brace is in the process of construction so

2
that the rigid tolerances now required can be obtained without machining, whereas in the case of cast center sill filler members, even under the best developed shop practices, the most practical method developed is to make the casting oversize and machine it to the required tolerances, which is expensive and frequently heavy losses of finished castings occur due to thick or thin or defective portions in the castings. Also the coring of rivet holes is undependable and inaccurate, making it necessary to drill the same, involving another expensive machine operation, whereas in the welded construction using rolled sections or plates, the holes can be punched in multiple with accuracy.

Another great advantage to my invention is that by making the center sill filler member and brace made up of various parts welded together the parts can be made of different grades of material as conditions require. The draft gear stop members, being subjected to heavy buffing and more wear than any other part of the filler member and brace, can be made of harder steel or a special steel alloy more suitable for that purpose, than the major portion of the filler member. Similarly the king pin supporting socket is subject to hard usage and it can be made of a steel alloy that is considerably stronger and lighter than the conventional grade of steel usually used for structural members at a smaller or at least no additional cost. Thus any part that would have hard usage or would be subjected to a particular kind of wear or stress, can be made of the particular alloy most suitable therefor in using my welded type of construction, and a much better structure having much longer life results.

Other objects and advantages of my invention will appear as the description of the drawings proceeds. I desire to have it understood, however, that I do not intend to limit myself to the particular details shown or described, except as defined in the claims.

Fig. 1 is a view taken partly in plan and partly in section, taken substantially on the line 1—1 of Fig. 3, of my improved center sill filler member, showing fragmentary portions of the center sill members associated therewith.

Fig. 2 is a view showing one of the side plate members in elevation, portions of the filler member and center sill being shown in section, the view being taken substantially on the line 2—2 of Fig. 1.

Fig. 3 is a transverse sectional view through the center sill, showing the filler member in end elevation as viewed

Fig. 4 is a section taken on the line 4—4 of Fig. 1.

Fig. 5 is a horizontal sectional view through the lower portion of one of the side plates.

Fig. 6 is a fragmentary sectional view taken on the line 6—6 of Fig. 3.

Fig. 7 is an end elevational view of one half of the transverse bracing and socket forming member.

Fig. 8 is a fragmentary top plan view of a modification of the rear end portion of the filler member.

Fig. 9 is a section taken on the line 9—9 of Fig. 8.

Fig. 10 is a fragmentary view partly in elevation and partly in section of a further modification, and

Fig. 11 is a fragmentary horizontal sectional view of a modification of the mounting of the stop plate on the center sill.

Referring in detail to the drawings, my improved filler member and brace is shown as being applied between a pair of center sill members 11, which are ordinarily made Z-shaped in cross section. A pair of side plates 12 are provided for securing to the center sill members 11 either by welding or riveting, as may be preferred. The side plates 12 are provided with upper inwardly directed flanges 13 and lower inwardly directed flanges 14. The flanges 14 are connected by means of a transversely extending plate-like member 15, which may be recessed at the opposite transverse edges thereof, as indicated at 24, to reduce the weight thereof and provide enlargements 16 at opposite sides of said plate-like member that are engaged with the lower faces of the lower flanges 14 and welded to said flanges. A pair of similar but oppositely directed members 17 are provided, which extend perpendicularly to the plate-like member 15 and have a pair of parallel legs 18 extending perpendicularly to the vertical walls of the side plates 12 connected by means of a transverse web portion 19. The bottom edges of the web portions 19 and the legs 18 are welded to the plate-like member 15 and the end edges of said legs 18 are welded to the vertical walls of the plate-like members 12.

The legs 18 are taller than the web portions 19, as will be obvious from Figs. 2, 4 and 7, each having a tapering extension 20, the top edge 21 of 50 which is welded to the flange 13 on the side plate 12 which the same engages. The flanges 13 are of substantially uniform width from end to end of the side plates 12, while the flanges 14 have the forward ends thereof of substantially the same width as the flanges 13, but are provided with inclined edges 22 to provide a narrower flange portion 23 extending to the rear end edges of said flanges. Said narrower flange portions 23 are provided with notches 25 for receiving the legs 18 60 of the channel members 17, said legs 18 being, preferably, welded to the flanges 14 at said notches 25.

A transversely extending bracing means is thus provided between the side plate members 12 made up of the plate-like member 15 and the paired members 11, the two members 11 together forming an H-shaped brace. The web portions 19 of said members 11 are provided with socket forming portions 26 pressed or otherwise formed therein, the two portions 26 of the two members 11 forming a socket providing a cylindrical passage 21 for the king pin, which is provided in the usual manner, also extending through the bolster, which is of the usual construction, as indicated

generally at 28. Preferably, a reinforcing member 60 is provided extending between the legs 18 from the web portion 19 to the side plates 12 at the upper end of the socket forming portions 26, which is an integral flange on the web portion 19 and socket portions 26, and is welded at the top or bottom side thereof to legs 18 and side plates 12, thus further reinforcing the transverse bracing means and the socket for the king pin. A brace is thus provided between the side plates that is H-shaped in both vertical and horizontal section. The transverse bracing plate 15 has a circular opening 29 therein aligning with the cylindrical passage 21 for passage of the king pin therethrough. The web portions 19 lie face to face on opposite sides of the socket forming portions 26 and are welded to each other, as indicated at 30. Thus the H-shaped members that form the bracing members together with the plate-like member 15, also serve as socket forming means for the king pin.

The plate-like members 12 have reduced rear end portions 31 and an inturned flange 32 that extends nearly vertical is provided along the edge portion of the plate-like member 12 below the reduced extension and extends to the reduced portion 23 of the bottom marginal flange 14. The reduced portions 23 of the flanges 14 and the flanges 32 at their points of engagement may be made continuous or welded to each other, if desired, to add to the rigidity of the plate-like members 12. The reduced end portions 31 of the plate-like members have portions 33 that are inclined toward each other and terminate in transversely extending portions 34 that align with each other and butt up against each other in edge to edge engagement, the same being, preferably, welded to each other at their points of engagement. The reduced portions 31 have inclined bottom edges that are provided with marginal flanges 35 that are continuations of the flanges 32 and which have upturned rear ends 36 that abut the portions 34 and are, preferably, welded thereto. The depending wall portions 34 are very short, as will be obvious from Fig. 2, and are in effect, downward extensions on the flanges 13, which have inclined portions 37 corresponding to the inclined portions 33 of the side plates and portions 38 directed toward each other and engaging edge to edge, which are, preferably, welded to each other at their points of engagement with each other.

The side plates 12 have inwardly directed flanges 39 at their forward ends, which are welded to the flanges 14 and 13, and have the draft gear stop plates 40 welded thereto. Said stop plates are further reinforced by means of channel members 41, which are provided with parallel legs 42, the extremities of which are welded to the vertical walls of the side plates 12. The channel members extend lengthwise of the side plates 12 with the end edges of the legs and the web portions thereof in engagement, respectively, with the plates 40 and the transverse bracing members 44, the flanges 39 being notched at 45 to receive the channel members 41, and said legs and web portions being welded to the plates 40, flanges 39 and the bracing member 44 at their points of engagement therewith. Thus additional transverse bracing means is provided for the draft sill between the plate-like members 12, and the rear stops for the draft gear are thoroughly braced so as to withstand any shocks to which the same are subjected.

Large openings 46 may be provided in the web

portions of the channel members 41 to provide access to the rivet openings 45 in case it is desired to rivet the combined center filler, bracing means and rear draft stop member to the center sills. Other rivet openings 47 may be provided at desired locations in the vertical walls of the side plates 12 and the flanges 13 for riveting the side plates to the vertical walls of the center sill members or the top flanges thereof.

Instead of using rivets, the filler member can be welded to the center sill members, in which case the openings may be of any desired shape and, preferably, much fewer in number and much larger than the openings 45 and 47. Welding the filler members to the center sill members is of great advantage, as it eliminates the large number of rivet openings necessary in a riveted construction, thus greatly strengthening the structure. In such case the edges of the flanges 13, 37 and 38 are welded to the center sill member 11, and the member 11 is welded to the side plates 12 at the junction of the flanges 14, 32, 33 and 35 with the body portions thereof. Also the stop plates 40' narrower than the stop plates 40, are provided so that the edge portions of the side plates can be welded to the sill members 11, as shown in Fig. 11.

It will be noted that a center sill brace and filler member is provided that is reinforced where this is necessary, without providing any excess weight, and that the bracing means between the side plates, the side plates themselves, and the bracing means for the draft stops are all made of a channel-shaped character providing greater strength and further when the parts are welded together a plurality of box-like bracing structures are provided, which give maximum strength for their weight. It will also be noted that the parts of the center sill filler member are few in number and are all of such a character that the same can be simply formed by forging or pressing operations, and that some of the parts can be made of ordinary stock material without performing any complex operations thereon, thus greatly reducing the cost of the filler member below that of previously known cast center sill filler members and welded members that require large numbers of small parts of unusual form, adding to the cost of manufacture thereof.

While the reduced rearward extension on the filler member formed of the inclined portions 33 and the connecting portions 34 is sometimes preferred, a similar structure can be produced, which will be lighter in weight and simpler to form and will serve substantially the same purpose as the structure shown in Figs. 1 and 2, such structure being shown in Figs. 8 and 9 in which the reduced extensions 31' inclining toward each other are provided with the flanges 37' and 35', similar to the flanges 37 and 35 previously described, but these terminate short of the inwardly directed portions 34 and 38, and a transversely extending bracing channel 48 is provided, which has a leg 49 extending perpendicularly to the web portion 50 thereof, and a leg 51 extending at an oblique angle thereto, the leg 51 being welded to the flange 35', as will be obvious from Fig. 9, at the forward extremity 52 of the reduced portion 31'. The rearward end 52 is further reduced, as will be obvious from Fig. 9, to provide an offset portion having an offset flange 53 so that the upper leg 49 of the channel member 50 can be assembled with the flange 37', so that the top portions of the leg 49 and said flanges 37' are flush with each other, the leg 49 being, preferably,

beveled at 54 to make a good joint. Said leg 49 is welded to the offset portion 53 at the beveled edge 54 thereof and also, preferably, at the points where the reduced ends 53 of the legs 37' and the legs 49 lie face to face. Rivet openings 47 may be provided in the leg 49 of the channel member for riveting purposes, if this is desired.

Ordinarily the entire reduced extension 31 can be eliminated without any loss in strength, if such extension is not necessary for any other purpose, and in Fig. 10 the side plate 12' is shown as terminating at the inwardly directed flange 32', which corresponds in position substantially to the flange 32. A bracing member 55, which is shown as a bar but may be of any desired cross sectional shape, extending transversely between the flanges 32' adjacent the upper ends thereof near their intersection with the flanges 13 of the side plate 12 provides transverse bracing means between the side plates 12' rearwardly of the bracing means made up of the channel members 17 and cooperates with the transverse bracing plate 15, which provides a transverse brace between the bottom portions of the side plates. Said transverse bracing member 55 is welded to the flange 32, as will be obvious from Fig. 10.

What I claim is:

1. A center sill filler comprising a pair of side plates having top and bottom flanges, and a bracing structure between said side plates, comprising a pair of members having legs extending between the flanges of said side plates and having web portions connecting said legs welded to each other back to back to provide a substantially H-shaped bracing structure between said side plates, said web portions having oppositely bowed formations therein forming a king-pin socket, said side plates extending both forwardly and rearwardly from said bracing structure, the rearward extensions of said side plates converging and having a transversely extending flanged bracing member welded thereto to connect the ends thereof.

2. A center sill filler comprising a pair of side plates having top and bottom flanges, and a bracing structure between said side plates, comprising a pair of members having legs extending between the flanges of said side plates and welded at their extremities to said side plates and having web portions connecting said legs welded to each other back to back to provide a substantially H-shaped bracing structure between said side plates, said web portions having oppositely bowed formations therein forming a king-pin socket, said side plates extending both forwardly and rearwardly from said bracing structure, the rearward extensions of said side plates tapering and converging and having a transversely extending flanged bracing member channel shaped in cross section welded thereto to connect the ends thereof.

3. A center sill filler comprising a pair of side plates having top and bottom flanges, and a bracing structure between said side plates, comprising a pair of members having legs extending between the flanges of said side plate and welded at their extremities to said side plates and having web portions connecting said legs welded to each other back to back to provide a substantially H-shaped bracing structure between said side plates, said web portions having oppositely bowed formations therein forming a king-pin socket, said side plates extending forwardly of said bracing structure and each having a vertical flange adjacent

the rear end of said bracing structure and a transverse bracing member welded to said vertical end flanges near the upper ends thereof to connect said side plates.

4. A bracing structure for center sills comprising a pair of members each having a pair of longitudinally spaced legs of substantially the height of said center sill extending transversely of said bracing structure and vertical web portions shorter than said legs connecting the same, said web portions extending longitudinally of said bracing structure and being welded back to back to provide a bearing structure substantially H-shaped in horizontal section, said web portions having oppositely bowed formations therein forming a king pin socket, and a horizontal web portion on each of said members extending from the top of said vertical web portion between each pair of said legs and welded thereto to provide a transverse brace between said legs between the top and bottom edges thereof, whereby said bracing structure is H-shaped in vertical longitudinal section on each side of said vertical web portions.

5. A center sill filler, comprising a pair of side plates having inwardly directed horizontal flanges extending longitudinally of said side plates at the top and bottom thereof, and a bracing structure between said side plates, comprising a pair of members each having a pair of vertical transversely extending legs, each leg having a portion extending from the bottom flange of one of said side plates to the top flange thereof and each welded at its top and bottom edge to side top and bottom flange, respectively, each leg having an outer vertical edge welded to one of said side plates, and each of said members having a vertical longitudinally extending web portion connecting said pair of legs at the inner ends thereof, said web portions being welded to each other back to back to provide a bracing structure substantially H-shaped in horizontal section between said side plates, said web portions having oppositely bowed portions therein forming a king pin socket.

6. A center sill filler, comprising a pair of side plates having inwardly directed horizontal flanges extending longitudinally of said side plates at the top and bottom thereof, and a bracing structure between said side plates, comprising a pair of members each having a pair of vertical transversely extending legs, each leg having a portion extending from the bottom flange of one of said side plates to the top flange thereof and each welded at its top and bottom edge to side top and bottom flange, respectively, each leg having an outer vertical edge welded to one of said side plates, each of said side members having a vertical longitudinally extending web portion connecting said pair of legs at the inner ends thereof, said web portions being welded to each other back to back to provide a bracing structure substantially H-shaped in horizontal section between said side plates, said web portions having oppositely bowed portions therein forming a king pin socket, each member having a brace plate extending horizontally from the top of its web portion to the legs thereon and to a side plate and welded to said web portions, legs and side plate to form a structure H-shaped in vertical section with said legs, and a brace plate underlying and welded to said bottom flanges and extending between the same under said pair of members with the bottom edges of said legs and web portions in engagement with and welded to said brace plate.

7. A center sill filler, comprising a pair of side plates having inwardly directed horizontal flanges extending longitudinally of said side plates at the top and bottom thereof throughout the length thereof, a bracing structure between said side plates, comprising a pair of members each having a pair of vertical transversely extending legs, each leg having a portion extending from the bottom flange of one of said side plates to the top flange thereof and each welded at its top and bottom edge to said top and bottom flange, respectively, each leg having an outer vertical edge welded to one of said side plates, and each of said members having a vertical longitudinally extending web portion connecting said pair of legs at the inner ends thereof, said web portions being welded to each other back to back to provide a bracing structure substantially H-shaped in horizontal section between said side plates, said web portions having oppositely bowed portions therein forming a king pin socket, said side plates extending both forwardly and rearwardly from said bracing structure, the rearward extensions of said side plates converging and having inturned ends on said converging portions welded to each other, and a bracing structure at the forward ends of said plates comprising a transversely extending portion spaced longitudinally from said first mentioned bracing structure.

8. A center sill filler, comprising a pair of side plates having inwardly directed horizontal flanges extending longitudinally of said side plates at the top and bottom thereof throughout the length thereof, and a bracing structure between said side plates, comprising a pair of members each having a pair of vertical transversely extending legs, each leg having a portion extending from the bottom flange of one of said side plates to the top flange thereof and each welded at its top and bottom edge to said top and bottom flange, respectively, each leg having an outer vertical edge welded to one of said side plates, and each of said members having a vertical longitudinally extending web portion connecting said pair of legs at the inner ends thereof, said web portions being welded to each other back to back to provide a bracing structure substantially H-shaped in horizontal section between said side plates, said web portions having oppositely bowed portions therein forming a king pin socket, said side plates extending both forwardly and rearwardly from said bracing structure, transverse biasing means connecting the rearward extensions of said side plates in spaced relation to said bracing structure, said side plates having vertical flanges on the forward ends thereof, draft gear stop plates welded to said vertical flanges and to said top and bottom flanges, channel shaped reinforcing members of uniform height having the forward ends thereof welded to said stop plates and the legs thereof welded to said side plates substantially midway of the height thereof, and transverse bracing means connecting the forward extensions of said side plates in longitudinally spaced relation to said bracing structure and the ends of said reinforcing members remote from said stop plates.

9. A center sill filler, comprising a pair of side plates having inwardly directed horizontal flanges extending longitudinally of said side plates at the top and bottom thereof, said bottom flanges having each a pair of notches therein, and a bracing structure between said side plates, comprising a pair of members each having a pair of vertical transversely extending legs, each leg hav-

ing a portion extending from the bottom flange of one of said side plates to the top flange thereof and each seated in one of said notches, each leg being welded at its top and bottom edge to said top and bottom flange, respectively, each leg having an outer vertical edge welded to one of said side plates, and each of said members having a vertical longitudinally extending web portion connecting said pair of legs at the inner ends thereof, said web portions being welded to each other back to back to provide a bracing structure substantially H-shaped in horizontal section between said side plates, said web portions having oppositely bowed portions therein forming a king pin socket.

10. A center sill filler comprising a pair of side plates having inwardly directed top and bottom flanges, and a bracing structure between said side plates connecting said side plates and flanges, said side plates extending forwardly from said bracing structure and having inwardly directed vertical flanges at the forward ends thereof, draft gear stop plates each welded to the vertical flange and to the top and bottom flanges of one of said side plates, said stop plates being carried solely by said side plates, and a U-shaped reinforcement for said stop plates welded thereto and to said side plates, substantially midway of the height thereof, said reinforcement having a pair of legs welded at one end to said stop plates extending lengthwise of said side plates and a transverse portion connecting the other ends of said legs and extending between said side plates between said bracing structure and said stop plates in longitudinally spaced relation to said bracing structure.

11. A center sill filler comprising a pair of side plates having inwardly directed top and bottom flanges, and a bracing structure between said side plates connecting said side plates and flanges,

said side plates extending forwardly from said bracing structure and having inwardly directed vertical flanges at the forward ends thereof, draft gear stop plates each welded to the vertical flange and to the top and bottom flanges of one of said side plates, said stop plates being carried solely by said side plates, a reinforcement for said stop plates comprising channel shaped leg portions of uniform cross section extending through said vertical flanges and having the forward end edges thereof welded to said stop plates and the legs thereof welded to said side plates substantially midway of the height thereof, and a transverse bracing portion connecting said leg portions of said reinforcing members at the other ends thereof and extending between said side plates between said bracing structure and said stop plates in longitudinally spaced relation to said bracing structure.

Certificate of Correction

Patent No. 2,569,372

September 25, 1951

THOMAS A. COLLISON

It is hereby certified that error appears in the printed specification of the above numbered patent requiring correction as follows:

Column 6, line 67, for "plate" read *plates*; column 8, line 52, for "biasing" read *bracing*;

and that the said Letters Patent should be read as corrected above, so that the same may conform to the record of the case in the Patent Office.

Signed and sealed this 29th day of January, A. D. 1952.

[~~SEAL~~]

THOMAS F. MURPHY,

Assistant Commissioner of Patents.
